UNITED STATES PATENT OFFICE

158,528

DAYLIGHT MOTION-PICTURE FILM PRINTER

Leo R. Streeter, North Hollywood, Calif., assignor,
by mesne assignments, to Bernard B. Korn, Los
Angeles, Calif.

Application November 5, 1948, Serial No. 149,490

Term of patent 14 years

(Cl. D61—1)

To all whom it may concern:

Be it known that I, Leo R. Streeter, a citizen of the United States, residing at North Hollywood, in the county of Los Angeles and State of California, have invented a new, original, and ornamental Design for a Daylight Motion Picture Film Printer, of which the following is a specification, reference being had to the accompanying drawing, forming part thereof.

Fig. 1 is a perspective view looking at the front of a daylight motion picture film printer showing my new design.

Fig. 2 is a front elevational view in a vertical position as compared to the disclosure in Fig. 1.

Fig. 3 is a rear elevational view in a vertical position, the salient features of the design being shown in full lines.

I claim:

The ornamental design for a daylight motion picture film printer, substantially as shown and described.

LEO R. STREETER.
